PACKAGING HEAVY, LEGGED ARTICLES

Howard J. Lacy, II, and Elmer C. Slaughter,
Indianapolis, Ind., assignors to U. S. Corrugated
Fibre Box Company, Indianapolis, Ind., a cor-
poration of Indiana

Application August 20, 1941, Serial No. 407,622

8 Claims. (Cl. 206—46)

Heretofore heavy legged articles, such as office desks, chairs, washing machines, etc., having horizontally extending elements between the legs comparatively near to the lower ends thereof, have been packaged in wooden crates with the finish of the article protected by paper or burlap wrappings and, in many instances, the lower ends of the legs have been connected by temporary horizontal members generally incorporated as elements of the enclosing crate. Such a package is heavy and relatively expensive and oftentimes, during transportation, the wrappings become punctured by elements which mar the finish of the article without leaving readily noticeable openings in the wrappings so that the receiver of the package is not forewarned of possible finish marrings. The cost of shipping such a package is relatively great because of the unavoidable weight and the space occupied thereby.

The object of our present invention is to provide a completely enclosing corrugated paper carton for such articles supplemented by corrugated paper supporting elements and filler elements of such character that when the article is enveloped and supported within the carton, the completed package will be of such character as to successfully withstand the heaviest transportation shocks to which it may be subjected and of such character that if it has been subjected to forces which probably resulted in injury to the finish of the article, the package will present such an appearance as to give readily discernible notice of the probability of such marring.

The accompanying drawings illustrate our invention as incorporated in a package containing a legged desk of that common type which comprises two parallel drawer cabinets and a connecting top.

Fig. 1 is a plan of such a package with the portions of the outer carton normally paralleling the top of the article in open position;

Fig. 2 is a similar plan of the carton inverted;

Fig. 3 is a fragmentary vertical section on line 3—3 of Fig. 1 but on a larger scale;

Fig. 4 a perspective view of one of the corner filler elements;

Fig. 5 a perspective view of one of the weight carrying elements with the parts thereof separated;

Fig. 6 is a perspective view of a modified form of weight supporting element; and

Fig. 7 is a perspective view of one of the portions of a corner filler element with the parts in partially folded positions.

In the drawings 10, 10 indicate the side walls,

11, 11 end walls, 12, 12 side wall top flaps, 13, 13 end wall top flaps, 14, 14 side wall bottom flaps, and 15, 15 end wall bottom flaps conveniently formed of one or more sheets of corrugated paper of such size as to receive the desired article 20, preferably with about one inch clearance all around.

We provide corner filler elements composed of two or more nested elements of the character illustrated in Fig. 7. These elements are formed of a single piece of corrugated paper folded along a medial line 21 to form two legs 22, 23 lying at right angles to each other. At one end leg 22 is provided with a similar flap 25, foldable along fold lines 26 to positions at right angles to the respective planes of the legs 22 and 23 with one flap overlying the other in planes at right angles to the two planes of the legs 22 and 23. Depending upon the character of the article to be packaged, two or more of such elements may be nested together, as shown in Fig. 4, and one of such units is placed over each corner of the table top after the table has been placed in the carton. The top flaps of the carton are then folded over and secured in place and the package inverted. In this position the top of the table or other article is supported by the overlying flaps 24, and 25 of the corner filler units and spaced from the top flaps of the carton a distance equal to the number of thicknesses of said corner filler flaps.

In order to support and protect the legged end of the article, a plurality of elements such as those illustrated in Figs. 5 or 6 may be used.

In Fig. 5, 30 indicates a strip of corrugated paper of desired width and length with the ends 31, 31 folded on fold lines 32, 32 to positions at right angles to the plane of the main body of the sheet and each of said ends is slotted at 33, 33 conveniently to one-half the height of said folded ends. A similar sheet of corrugated paper 35 has its ends 36, 36 similarly folded on fold lines 37, 37 with said ends 36, 36 slotted at 33, 33 so that the two pieces may be assembled and interlocked in the plane of the slots 33, 33 with the free edges 40 of ends 31 resting against the inner surface of strip 35 and the free edges of ends 36 resting upon the inner surface of strip 30.

In the case of the packaging of a desk, such as is illustrated, where each pedestal end is provided with three legs, 40, 41 and 42, the weight supporting element just described has its part so proportioned that the width of strip 35 will fit snugly between legs 40 and 41 in contact with the bottom 30' of the desk and extending across the fore-and-aft dimensions of the desk and there-

beyond either to the side walls of the main carton or spaced therefrom one or more thicknesses of the corrugated paper used to produce the corner filler elements already described. The width of element 30 will be such as to fit snugly between the legs 40, 42 and the length such as to extend beyond leg 41 at one end and beyond legs 40, 42 at the other end, either to the adjacent end wall of the carton or spaced therefrom one or more thicknesses of the sheet material used to produce the corner filler units.

The depth of the unit composed of the two elements 30, 35, when assembled, will be somewhat greater than the extent of the leg below the plane of the article bottom 30' or any horizontally extending leg connecting element which connects the legs adjacent the lower ends thereof. This distance will, of course, vary with the character of the article which is being packaged and may, in some instances, be as much or perhaps a little more than half the total height of the article being packaged.

Instead of weight supporting elements of the character shown in Fig. 5, we may use elements such as are shown in Fig. 6. Here a strip of corrugated paper 50 has its ends 51, 51 folded to positions at right angles to the plane of the main body 50 on fold lines 52, 52 and these ends 51 are vertically slotted at 33 as in Fig. 5. A companion member 55 with one end 56 folded on fold line 57 is slotted at 33, 33 so as to mate with the slots 33 of the element 50 with the free edge 58' of portion 56 resting on the inner surface of portion 50, portion 55 resting upon the ends of portions 51, 51. Here also the total depth of the unit 50—55 will be such as to be slightly greater than the projection of the leg of the article to be packaged below the lowermost connecting horizontal member.

For a purpose which will appear, we prefer to form the slot 33 in one of the ends 51 at a greater distance from the adjacent edge of said end than the spacing of the companion slot 33 in the other end 51.

Closely adjacent the fold line 57 the main body 55 is pierced by a plurality of X-incisions 60 which thus form four triangular flaps 61, 61 between which a leg of the article to be packaged may be projected and, in order to make this unit readily adaptable for use in various positions, the main body of sheet 50 closely adjacent the inner surface of part 56 of sheet 55 will be similarly incised to provide a plurality of leg receiving openings in sheet 50. These last-named incisions may, in some instances, be aligned with the incisions 60 in sheet 55.

Weight supporting elements of the character shown in Fig. 6 may be associated with the article being packaged, with a leg of that article in the open corner between the adjacent projected ends of parts 51 and 56, as shown at A (Fig. 2) or in the position shown at B (Fig. 2), where one of the legs of the article is projected through one of the incisions 60 and, in that event, the weight supporting filler, because of relationship of the slots 33 already described, may be set at a slight angle to the horizontal dimension of the article being packaged.

After the weight supporting elements have been placed in position as described, corner filler elements of the character shown in Fig. 3 are placed in position over the ends of any of the legs which may be exposed, whereupon the bottom flaps of the main carton are folded and secured in place. The completed carton may then be reverted.

Conveniently, the end walls of the main carton, near their tops, may be provided with hand holes which will facilitate handling the completed carton.

5 We have found that the package of the above-described character containing an ordinary office desk may be readily handled, because of its comparative lightness, and that it may be even rolled down a flight of stairs without damage to the desk so that the package, although composed entirely of corrugated paper and containing articles weighing several hundred pounds, nevertheless meets all of the shipping requirements of common carriers.

15 Such a package is much lighter than crates now ordinarily used, the legs are so thoroughly protected that no shipping stresses can be transmitted thereto in such way as to wrack the furniture or break the legs and the several walls of the enclosing carton are so distantly spaced from the article that no damage can occur to the finish or construction of the article except as a result of such a puncture of the walls of the carton as would inevitably be immediately noticed so that the receiver would be put upon his guard in accepting receipt of the package.

20 Through the use of corner pads and weight supporting elements in the manner disclosed, it is possible to use cartons of uniform size to accommodate articles of various sizes within the capacity of the carton.

25 The air space which is insured entirely around the article very materially reduces the possibility of cracking of the finish of the article.

30 Heavy articles for which the above-described structures are primarily designed have heretofore been quite generally enclosed in part or whole by excision packing and burlap wrappings often enclosed in wooden crates. Such packages not only provide a distinct fire hazard but also are of such character that when once opened for inspection of the enclosed articles cannot be readily reassembled for reshipment. Our package, on the contrary, is of such character that it can be readily opened for inspection of the enclosed articles and readily reclosed for reshipment.

35 We claim as our invention:

1. A filler and cushion unit for inclusion in a carton with a packaged article, comprising two sheets of corrugated paper each folded on an intermediate fold line to form two portions at right angles to each other with one portion of each sheet slotted at an intermediate point in its length inwardly toward but not to a fold line and the two sheets interlocked at their slots so that a free edge of each sheet overlies and bottoms on an inner surface of a companion sheet.

2. A filler and cushion unit for inclusion in a carton with a packaged article, comprising two sheets of corrugated paper, one sheet having its opposite ends upturned and each upturned end slotted at an intermediate point in its length inwardly toward a fold line, and the other sheet folded on an intermediate fold line and one end inwardly slotted toward but not to the fold line at two points intermediate its length and registerable with the slots of the first-mentioned sheet, one edge of the second-mentioned sheet overlying and bottoming on an inner surface of the first-mentioned sheet, and one portion of the second-mentioned sheet resting upon the ends of the two upturned ends of the first-mentioned sheet.

3. A filler and cushion unit as specified in claim 2, wherein an unslotted portion of one sheet

incised adjacent a fold line by crossed incisions permitting projection therethrough of an article leg.

4. A filler and cushion unit for inclusion in a carton with a packaged article, comprising two interlocked sheets of corrugated paper, each sheet having its ends folded in the same direction on intermediate fold lines and each of said ends being inwardly slotted at an intermediate point in its length toward but not to a fold line by two slots, the free ends of each sheet overlying and bottoming on an inner face of the companion sheet.

5. A package comprising a carton of corrugated paper, a legged article therein having horizontally extending elements between the legs substantially below the top of the article, and a unit of corrugated paper interposed between legs of the article and between such horizontally extending elements and a wall of the carton and supporting the weight of said article adjacent a leg of the article, said unit being composed of two sheets of corrugated paper as specified in claim 1.

6. A package comprising a carton of corrugated paper, a legged article therein having horizontally extending elements between the legs substantially below the top of the article, and a unit of corrugated paper interposed between legs of the article and between such horizontally extending elements and a wall of the carton and supporting the weight of said article adjacent a leg of the article, said unit being composed of two sheets of corrugated paper as specified in claim 2.

7. A package comprising a carton of corrugated paper, a legged article therein having horizontally extending elements between the legs substantially below the top of the article, and a unit of corrugated paper interposed between legs of the article and between such horizontally extending elements and a wall of the carton and supporting the weight of said article adjacent a leg of the article, said unit being composed of two sheets of corrugated paper as specified in claim 4.
8. A package comprising a carton of corrugated paper, an article therein comprising a main body and projecting legs, and a weight-supporting unit of corrugated paper comprising two interlocked members, the first member having its opposite ends bent to positions at right angles to the medial part thereof and each slotted at an intermediate point in its length toward but not to said medial part, and the second member folded along an intermediate line to present two portions at right angles to each other, one of said portions being slotted at two points intermediate its length toward but not to the other portion and interlocked at said slotted points with the slotted points of the first member, and the other portion of said second member overlying the upturned edges of the first member and incised by crossing incisions, between the upturned edges of the first member and a leg of the article projected through said incisions.
